CLAMP FOR CONCRETE FORM WORK

Eric Percival Muntz, Hamilton, Ontario,
Canada

Application April 25, 1935, Serial No. 18,143

13 Claims. (Cl. 24—136)

My invention relates to improvements in clamps for concrete form work, and the object of my invention is to design a clamp for attachment upon the tie rods which I use for retaining form panel and other cribbing structures against movement, as illustrated and described in my United States Patent No. 1,991,256.

The object of my present invention is to provide a clamp which is particularly designed for use upon rods of a relatively small diameter, i. e. in the vicinity of a quarter of an inch, the rods or wire being made of carbon steel of high tensional strength.

A further and very particular object of my invention is to furnish a clamp of a simple and strong construction, that will withstand rough handling, severe strain, and repeated use without impairment of its clamping efficiency.

Another object of my invention is to only use two movable jaws in the clamp, and for the ready insertion of rod into the clamp, to provide a rubber jaw engaging member for resiliently retaining the jaws in a spaced apart position.

A still further object of my invention is to slidably position each jaw in its own housing, and to draw the two housings together for clamping the jaws upon a rod.

With these and other objects in view, my invention further consists in the construction and arrangement of the several parts all as hereinafter more particularly described and illustrated in the accompanying drawing in which:

Figure 1 is a vertical cross-sectional view through a pair of walings and a fragmentary portion of a form panel, showing a tie rod extending through the form panel and between the walings, together with my clamp positioned upon the outer end of the rod and abutting the outer faces of the walings.

Figure 2 is a front elevational view of my clamp, the rod having been removed.

Figure 3 is a vertical cross sectional view through the clamp, taken through the line 3—3, Figure 2.

Figure 4 is a horizontal cross-sectional view through the clamp taken through the line 4—4, Figure 2.

Figure 5 is a rear elevational view of my clamp.

Figure 6 is a perspective view of the rubber jaw cushion used in my clamp.

Figure 7 is a perspective view of one of the clamp jaws, and

Figure 8 is a reduced front elevational view of an alternative clamp construction wherein a ring

clamp is used for drawing the clamp housings together in lieu of the two bolts shown in the other construction.

Like characters of reference indicate corresponding parts in the different views of the drawing.

The clamp housing is comprised of two members of substantially the same form and size, and each member contains one of the two jaws. The members each consist of a back plate 1 and corresponding ribs 2 protruding forwardly from the outer faces of the back plates intermediately of their height. The ribs 2 are substantially parallel, and the housing members are connected by a pair of draw bolts 3 extending through a pair of orifices 4 in each of the ribs.

The upper rib 2 in its bottom face and the lower rib 2 in its top face are each formed with a substantially centrally positioned inclined jaw supporting member 5, wherein the inclined faces 6 of such members converge rearwardly. The outer edges of the ribs each carry a pair of lugs 7 and 8, the lugs on the top rib extending downwardly, and the lugs on the bottom rib extending upwardly. The lugs 7 and 8 are parallel and spaced apart to form slots 9 and the lugs 7 are of greater length than the lugs 8.

The two jaws 10 carried within the housings are of truncated longitudinal wedge form and of rectangular cross section. The lower inclined faces 11 of the jaws rest upon and have the same inclination as the inclined faces 6 of the jaw supporting members 5, so that the serrated faces 12 of the jaws are parallel. The forward and thick ends of the jaws are formed with portions 13 reduced in width to be slidably contained within the slots, the shoulders 19 bearing against the inner faces of the lugs 7 and 8.

The jaws 10 are shorter in length than the distances between the inner faces of the lugs 7 and 8 and the front faces of the plates 1, and a rubber cushion is interposed between the rear ends of the jaws and the front faces of the plates. The cushion is of a form as shown in Figure 6 and comprises a central portion 14 against which the rear end faces 15 of the jaws rest and having a central orifice 16 through which a contained tie rod can extend. The two vertical side portions 17 of the cushion are of increased thickness whereby shoulders 18 are formed and between which the ends of the jaws are held against side play. For retaining the serrated faces 12 of the jaws in a spaced apart relationship, I furnish a pair of forwardly projecting rubber pads 19 in the vertical centre of the forward face of the 55

portion 14 of the cushion. These lugs are spaced apart horizontally of the orifice 16 and are sandwiched, in spaced apart relationship to one another, between the jaws.

5 Upon reference to Figure 5 wherein a rear view of the clamp is shown, it will be seen that the opposing edges of the plates 1 are staggered about a central rod receiving orifice formed by the two substantially semi-circular indentations 21 in the 10 centres of the plate edges. The plates are normally spaced apart sufficiently to permit them to approach one another without contact upon the bolts 3 being drawn up to tighten the clamp.

The operation of my clamp is as follows:—

15 In Figure 1, I show a pair of wales 22 normally positioned upon the outside of a form panel 23, and a tie rod 24 extending through an orifice 25 in the panel and between the wales, with its outer end projecting beyond the wales. Before 20 positioning the clamp upon the outer end of the rod, the bolts 3 of the clamp are loosened so that the jaws are pushed apart by the rubber lugs 19 and are also pushed to the forward end of the clamp housings by the portion 14 of the rubber 25 cushion. The clamp is then positioned upon the rod, the rod being inserted between the plates 1 through the orifice 20, through the cushion orifice 16, between the serrated jaw faces 12, and projecting between the lugs 8. The clamp is 30 pushed along the rod until the upper clamp plate 1 abuts the outer face of the top wale 22 and the lower clamp plate 1 abuts the outer face of the lower wale 22. The bolts 3 are then tightened up, the heads 26 of the bolts being held 35 against rotation by the shoulder 27 formed on the lower plate 1. Upon tightening of the bolts, the jaws, already moved to the limit of their spaced apart relationship by the rubber element, bite into and clamp the rod.

40 It will be understood, upon reference to the Figure 1, that any inward pull upon the rod will tend to move the jaws with the rod, and that any inward movement of the jaws upon their inclined supports 6 will cause the jaws to move 45 towards one another and increase their grip upon the rod.

Furthermore as the bolts 3 are a loose fit in the orifices 4, the separated plates 1 abutting the separated wales 22 will under any inward 50 pull of the rod have a tendency to mutually arch inwardly, so that the outer ends of the ribs 2 will slightly swing together and in so doing increase the grip of the jaws upon the rod. To release the clamp, it is only necessary to loosen the bolts 3.

55 In Figure 8, I show an alternative construction wherein I provide a ring clamp 28 surrounding the lugs 2 in place of the bolts 3, the bottom of the ring bearing against the bottom of the lower 60 rib 2, and the screw 29 bearing against the top face of the upper rib 2. The tightening of the screw 29 draws the lugs 2 together.

Although I have illustrated and described my clamp as used in conjunction with tie rods for 65 concrete form work, it will be appreciated that it can be put to other use without departing from the spirit of my invention as set forth in the appended claims.

What I claim as my invention is:

70 1. A rod clamp for abutting wales and the like comprising a plurality of jaw housings moveable towards one another, a wedge-shaped jaw slidably contained in each housing, a rubber cushion bearing against the ends of the jaws and tending 75 to slide and move them apart, wale engag-

ing back plates against which the rubber cushion bears, and means for simultaneously moving the housings and jaws towards one another into the clamping position.

2. A rod clamp for abutting wales and the like 5 and having a rod-receiving orifice extending therethrough, a plurality of wedge-shaped jaws contained within the clamp about the rod receiving orifice, inclined faces in the clamp diverging from the rod orifice and upon which the jaws 10 slidably rest, a rubber cushion having a rod engaging orifice therein and tending to slide the jaws apart along the faces, a wale engaging back plate against which the rubber cushion bears, and a clamping element acting transversely of 15 the jaws and a contained rod for moving the jaws towards the rod.

3. A rod clamp for abutting wales and the like and having a rod-receiving orifice extending therethrough, a plurality of wedge-shaped jaws 20 contained within the clamp about the rod receiving orifice, inclined faces in the clamp upon which the jaws slidably rest, resilient means contained between the jaws and retaining them against the inclined faces, resilient means tending to slide 25 the jaws along the faces, and a clamping element acting transversely of the jaws and a contained rod for moving the jaws towards the rod.

4. A rod clamp for abutting wales and the like and having a rod-receiving orifice extending 30 therethrough, a plurality of wedge-shaped jaws contained within the clamp about the rod receiving orifice, inclined faces in the clamp upon which the jaws slidably rest, a rubber pad contained between the jaws and retaining them 35 against the inclined faces, a rubber cushion contacting the ends of the jaws and tending to slide them along the faces, and a clamping element acting transversely of the jaws and a contained rod for moving the jaws towards the rod.

5. A rod clamp for abutting wales and the like 40 comprising a plurality of jaw housings moveable independently of one another, a threaded clamping member engaging the housings for drawing them together, a wedge-shaped jaw slidably contained within each housing, an inclined face in each housing upon which a jaw slides, and a rubber cushion extending between the housings and contacting the ends of the jaws to slide them along the faces.

6. A rod clamp for abutting wales and the like comprising a plurality of jaw housings moveable independently of one another, a threaded clamping member engaging the housings for drawing them together, a wedge-shaped jaw slidably contained within each housing, an inclined face in each housing upon which a jaw slides, a rubber cushion extending between the housings and contacting the ends of the jaws to slide them along the faces, and a rubber pad contained between 60 the jaws for retaining them against the inclined faces.

7. A rod clamp for abutting wales and the like and having a rod receiving orifice extending therethrough, and comprising a pair of wale 65 abutting plates lying substantially in the same plane, a rib extending from the face of each plate, a bolt extending through orifices in the ribs and positioned substantially parallel to the plates, an inclined face formed on the inner face of 70 each rib, a wedge-shaped jaw positioned upon each inclined face, and a rubber pad contained between the jaws for retaining them apart and against the inclined faces.

8. A rod clamp for abutting wales and the like 75

and having a rod-receiving orifice extending therethrough, and comprising a pair of wale abutting plates lying substantially in the same plane, a rib extending from the face of each plate, 5 a bolt extending through orifices in the ribs and positioned substantially parallel to the plates, an inclined face formed on the inner face of each rib, a wedge-shaped jaw positioned upon each inclined face, a rubber pad contained between the jaws for retaining them apart and against the inclined faces, and a rubber cushion having a rod receiving orifice therein and extending between the ribs and contacting the ends 10 of the jaws to slide them along the inclined faces.

9. A rod clamp for abutting wales and the like and having a rod-receiving orifice extending therethrough a plurality of wedge-shaped jaws contained within the clamp about the rod receiving orifice, inclined faces in the clamp upon which the jaws slidably rest, resilient rubber means extending from jaw to jaw for retaining them apart and also tending to slide the jaws along the faces, and a clamping element acting transversely of the jaws for moving them towards each other.

10. A rod clamp for abutting wales and the like comprising a pair of wale abutting plates lying substantially in the same plane, a rib extending from the face of each plate, an inclined face formed on the inner face of each rib, a wedge shaped jaw positioned on each inclined face, a pair of inwardly extending lugs carried upon the outer end of each rib to form guides for the reception of a rod through the clamp, and a clamping element acting transversely of the ribs, jaws and a contained rod for moving the jaws towards the rod.

11. A rod clamp as claimed in claim 10 wherein the wale abutting plates lie edge to edge, the opposed edges of the plates being formed with two indentations which together form a rod receiving orifice.

5

12. A rod clamp for abutting wales and the like comprising a pair of wale abutting plates lying substantially in the same plane, a rib extending from the face of each plate, an inclined face formed on the inner face of each rib, a wedge shaped jaw positioned on each inclined face, a pair of inwardly extending lugs carried upon the outer end of each rib to form guides for the reception of a rod through the clamp, one rib of each pair being longer than the other and the 15 longer rib of one pair being positioned oppositely to the shorter rib of the other pair whereby the space between the inner sides of the two long ribs constitutes a rod receiving orifice, and a 20 clamping element acting transversely of the ribs, jaws and a contained rod for moving the jaws towards the rod.

13. A rod clamp for abutting wales and the like comprising a pair of wale abutting plates 25 lying substantially in the same plane, a rib extending from the face of each plate, an inclined face formed on the inner face of each rib, a wedge shaped jaw positioned on each inclined face, a pair of inwardly extending lugs carried 30 upon the outer end of each rib to form guides for the reception of a rod through the clamp, reduced forward ends upon the jaws slidably projecting into slots formed between the lugs, and a 35 clamping element acting transversely of the ribs, jaws and a contained rod for moving the jaws towards the rod.

ERIC PERCIVAL MUNTZ.
